[57] CLAIM

The ornamental design for a fishing rod light, as shown
and described.

DESCRIPTION

FIG. 1 is a perspective view of a fishing rod light showing
my new design, the fishing rod being shown in
broken lines for illustrative purposes only;

FIG. 2 is an elevational view thereof as seen from the
side shown in FIG. 1 on an enlarged scale;

FIG. 3 is an elevational view thereof as seen from the
opposite side on an enlarged scale;

FIG. 4 is an end elevational view thereof on an enlarged
scale;

FIG. 5 is the opposite end elevational view thereof on
an enlarged scale;

FIG. 6 is a bottom plan view thereof on an enlarged
scale;

FIG. 7 is a top plan view thereof on an enlarged scale;

FIG. 8 is a perspective view thereof as seen from the
side opposite that shown in FIG. 1 on an enlarged scale.
